What is claimed is the ornamental design for adjustable head wear, as shown and described.

DESCRIPTION

FIG. 1 is a perspective view of adjustable head wear, illustrated with tie straps of the design in a tied configuration, showing the new design;

FIG. 2 is a left-side elevational view thereof;

FIG. 3 is a right-side elevational view thereof;

FIG. 4 is a front elevational view thereof;

FIG. 5 is a front elevational view thereof, illustrated with the tie straps in an untied configuration;

FIG. 6 is a rear elevational view thereof, illustrated with the tie straps in the tied configuration;

FIG. 7 is a top plan view thereof; and,

FIG. 8 is a bottom plan view thereof.

The broken lines showing a person in FIGS. 1-6 are included for the purpose of illustrating the invention in use, and form no part of the claimed design.
